Greentree and Pegeer

ATTORNEY

UNITED STATES PATENT OFFICE.

HARRY SHULMAN, OF NEW YORK, N. Y.

PAINTBRUSH.

Application filed June 11, 1925. Serial No. 36,315.

To all whom it may concern:

Be it known that I, HARRY SHULMAN, a citizen of the United States, and a resident of the city, county, and State of New York, ⁵ have invented a new and useful Improvement in Paintbrushes, of which the following is a specification.

This invention relates to the manufacture of brushes and more particularly to paint ¹⁰ brushes or the like.

The manufacture of paint brushes such as used by artists and for the finer grades of painting, it is desirable to produce a brush which will have a pleasing and symmetric ¹⁵ appearance and at the same time have a maximum practical value.

Ordinarily when making a brush the bristles or tuft may be enclosed in a metal ferrule and vulcanized therein. This ferrule is ²⁰ then inserted in an outer casing having a handle. An edge of the casing is then crimped or beaded to prevent outward movement of the ferrule which secures the bristles. The ferrule is further secured by soldering.

When producing a brush without the use of an inner ferrule, the bristles are introduced into an outer casing and vulcanized therein. This method, however, although ³⁰ desirable from a manufacturing standpoint, requires the use of nails which pass through the casing and present a series of irregularities, thus marring the appearance of the outer surface of the casing and destroying the ³⁵ desirable unbroken surface thereof.

An object of the present invention is, therefore, to provide means for producing a brush, the bristles or tuft of which may be vulcanized directly in an outer ferrule or ⁴⁰ casing and held from displacement without the necessity of piercing the casing.

Another object of the invention is to provide a brush of a simple and practical construction having a ferrule or casing with a ⁴⁵ smooth outer surface.

A further object of the invention is to provide a brush ferrule having internal structure to which a tuft of bristles may tenaciously adhere when vulcanized.

⁵⁰ A still further object of the invention is to provide a brush ferrule having locking members about which the bristles of a brush may be vulcanized.

Other objects and advantages will be apparent as the description proceeds.

In practicing the present invention a ferrule is provided with relatively thin cross pieces preferably extending transversely of the ferrule. Ends of the cross pieces which may be termed locking members are suitably ⁶⁰ fastened to opposite interior surfaces of the ferrule. The bristles constituting a brush may then be inserted into the ferrule and about the cross pieces and then vulcanized ⁶⁵ in the usual manner.

By reason of the present construction, the vulcanizing operation results in a bonding of the tuft of bristles to the cross pieces since the vulcanizing material adheres firmly to the cross pieces and to the adjacent bristles ⁷⁰ which are held in a hard solid mass.

The locking-members as provided by the present invention not only provide a better appearing brush than when nails are employed, but a further advantage is attained ⁷⁵ in the bonding of the cross pieces to the bristles. This is not possible when nails are used, since it is obvious that a nail driven through the vulcanized portion of the tuft is disposed in an aperture slightly larger in ⁸⁰ diameter than the nail and any pull tending to remove the bristles from the ferrule makes each nail a cutting edge since it has no union with the vulcanized portion of the brush.

The invention will be more fully understood by reference to the accompanying drawing, in which

Fig. 1 is a side view of a brush embodying the present invention;

Fig. 2 is a transverse cross section taken on lines II-II in Fig. 1; and

Fig. 3 is a perspective view of a casing having locking members therein.

The present invention may be applied to ⁹⁵ various types of brushes. The one shown in the drawing includes the usual handle 5 attached to a ferrule or casing 6 in which a tuft of bristles may be vulcanized.

In accordance with the present invention ¹⁰⁰ the bristles are secured or locked from displacement by locking-members 8 and 9 which may bridge the space between the walls 10 and 11 of the casing 6. Any desirable number of locking members may be employed and as shown the two members 8 and 9 may be part of a continuous strip 12, a portion of which extends across a seam 13 of the casing. The said strip may be provided with lips or flanges 14 and 15. The ¹⁰⁵ 110

strip 12 may be of such proportions as to snugly fit the casing with the flanges 14 and 15 and the portion of the strip opposite thereto in contact with the inner surfaces of the walls 10 and 11 of the casing 6. The strip may be secured in any suitable manner as by soldering.

When the end 16 of a tuft of bristles has been inserted in the casing, the bristles will be disposed along the sides of the strip. The portion 16 may then be vulcanized and it will be readily appreciated that when the portion 16 of the brush is solidified in a compact mass about the locking members 8 and 9, the adherence of the bristles to the relatively large area of the strips by reason of the vulcanizing results in a strong bond and the tuft of bristles is held from removal from the casing.

By reason of the present invention I am able to make a brush of pleasing appearance and at the same time retain the required ruggedness and durability.

Although a preferred embodiment of the invention is shown and described herein, it is to be understood that such modifications may be made therein as do not depart from the spirit or scope of the appended claims.

What is claimed is.

1. A paint brush comprising a split tubular ferrule, a locking member in said ferrule, said member comprising a bent metallic strip having a relatively long section extending across and secured to the contiguous edges of the ferrule, portions at opposite ends of said section extending at right angles from said section and to the opposite wall of the ferrule, said portions being secured to said opposite wall and bristles secured in and projecting from said ferrule. 30 35

2. A paint brush comprising a split tubular ferrule, a locking member in said ferrule, said member comprising a bent metallic strip having a relatively long section extending across and secured to the contiguous edges of the ferrule, portions at opposite ends of said section extending at right angles from said section and to the opposite wall of the ferrule, said portions having foot pieces integral therewith and secured to the said opposite wall and bristles secured in and projecting from said ferrule. 40 45

In testimony whereof, I have hereunto subscribed my name this 3rd day of June, 1925.

HARRY SHULMAN.
